UNITED STATES PATENT OFFICE.

JOSEPH D. GALLAGHER, OF GLENRIDGE, NEW JERSEY.

BRAKE-SHOE.

No. 858,067.

Specification of Letters Patent.

Patented June 25, 1907.

Application filed February 19, 1906. Serial No. 301,732.

To all whom it may concern:

Be it known that I, JOSEPH D. GALLAGHER, a citizen of the United States and a resident of Glenridge, in the county of Essex and 5 State of New Jersey, have made and invented certain new and useful Improvements in Brake-Shoes, of which the following is a specification.

My invention relates to an improvement 10 in brake shoes, and method of forming the same, and more particularly to that kind or style comprising a wearing sole usually formed of cast metal, and a strengthening plate or back made of steel or other malleable or ductile metal, the object of the same 15 being to so construct the shoe that when the wearing sole has been worn down, the steel or other metal back may be easily and readily detached therefrom and again used in connection with another sole.

With this and other ends in view, the invention consists in certain novel features of construction and combination of parts, as 20 will be hereinafter fully described and specifically pointed out in the claims.

In the accompanying drawings, Figure 1 is 25 a plan view of the back plate prior to its attachment to the wearing sole. Fig. 2 is an edge view thereof. Fig. 3 is a plan view 30 showing the plate in position upon the wearing sole, prior to locking the same together. Fig. 4 is a longitudinal sectional view thereof taken on the line 4—4 of Fig. 3. Fig. 5 is a plan view of the shoe showing the plate attached to the wearing sole. Fig. 6 is a sectional view taken on the line 6—6 of Fig. 5. Fig. 7 is a sectional view taken on the line 35 7—7 of Fig. 5. Fig. 8 is a perspective view thereof.

Referring to the drawings, A represents 40 the body or wearing sole of the shoe made of any desired metal or metals, preferably cast iron, and having formed on the back thereof the lug B extending nearly the entire length 45 of the shoe. The sides of the lug B converge from the center of the shoe toward the ends thereof, and are undercut, as illustrated at a, Fig. 7. If desired, the end portions b of this lug may be slightly increased in height over 50 the central portion thereof, the height of the extreme ends c being still further increased in order to form guide lugs for the brake head, (not shown), similar to those formed on shoes of ordinary construction.

To the wearing sole A is secured the 55 strengthening plate or back C, made of steel

or other malleable or ductile metal, this plate being first blanked out, as illustrated in Figs. 1 and 2, that is, with the elongated openings d, the sides or edges of which converge from the center toward the outer ends of the plate, and with the contracted openings e, which latter in the finished shoe, form a passage-way through the attaching lug for a key wherewith to lock the same to a brake head. 60 The sides or edges of these openings are beveled, in order to conform to the undercut edges of the lug B, and thereby lock the plate to the wearing sole, as hereinafter described.

In assembling the parts, the plate C is preferably first heated to such a temperature as will permit it to be easily and readily bent or shaped into its finished form, and then placed upon the back of the wearing sole A, as illustrated in Figs. 3 and 4, the plate being curved 70 in its length to conform to the curvature of the wearing sole A, in which position the lug B will extend through the openings d, the ends of the plate extending over and beyond the ends of the sole A. By means of suitable 75 dies (not shown), the ends of the plate C are then brought together, either by raising the central portion of the plate, or by forcing or crowding said ends toward each other, whereby the beveled edges of the openings d tightly 80 engage with the undercut sides and ends of the lug B, and securely lock the plate to the wearing sole. As the ends of the plate C are thus brought toward each other to effect a locking with the wearing sole, the central portion of the plate is simultaneously bent or 85 curved upwardly, forming the attaching lug D, the restricted openings e forming a passage-way through the latter for the key (not shown), wherewith to attach the shoe to the 90 brake head, the extreme ends of the plate being turned or bent upwardly to form the end stops f.

If desired, the end stops f may be bent upwardly, and the lug D partially formed before the plate is placed in position on the wearing sole, it being essential, however, that the ends of the plate be separated to such an extent that the lug B will pass through the openings d in order to effect a proper assembling of the parts.

After the wearing sole has been worn comparatively thin in service, a small portion or section may be broken from the center thereof, whereupon the ends of the sole may 110 be driven toward each other until they are disengaged from the beveled edges of the

openings *d* in the plate C, whereupon the latter may be pressed into its original shape, as illustrated in Figs. 1 and 2, or the ends sufficiently separated to permit of its use upon a new wearing sole.

Having fully described my invention, what I claim as new and desire to secure by Letters Patent, is:—

1. The method hereinbefore described consisting in placing the plate upon the back of the wearing sole and secondly bringing the ends of said plate toward each other, whereby to lock the latter to said wearing sole and simultaneously form an attaching lug for the brake head.

2. The method hereinbefore described consisting in first heating the plate, secondly placing the same on the back of the wearing sole, and finally bringing the ends of said plate toward each other, whereby to lock the same to the back of the wearing sole.

3. The method hereinbefore described consisting in placing the plate while hot, upon the back of the wearing sole and subsequently

bringing the ends toward each other for locking said plate to the back of said wearing sole and bending the extreme ends of said plate to form end stops.

4. The method hereinbefore described, consisting in placing the plate while hot, on the back of the wearing sole and subsequently bringing the ends of said plate toward each other whereby to lock it to said wearing sole and simultaneously form end stops and a central lug for attachment to the brake head.

5. The method hereinbefore described, consisting in first placing the plate while hot, on the back of the wearing sole and subsequently bending said plate whereby to lock the same to said sole.

Signed at New York, borough of Manhattan, in the county of New York, and State of New York, this 16th day of February, A. D. 1906.

JOSEPH D. GALLAGHER.
